[57] CLAIM

The ornamental design for a typewriter, as shown and described.

DESCRIPTION

FIG. 1 is a right front perspective view of a typewriter showing our new design; the keyboard being continuous over the span indicated by dot-dash lines for ease of illustration.

FIG. 2 is a left front perspective view thereof;

FIG. 3 is a left rear perspective view thereof;

FIG. 4 is a right rear perspective view thereof;

FIG. 5 is a bottom plan view thereof;

FIG. 6 is a front perspective view of a typewriter without the sound hood as shown in FIGS. 1-4, showing our new design;

FIG. 7 is a left front perspective view thereof;

FIG. 8 is a left rear perspective view thereof; and

FIG. 9 is the right rear perspective view thereof.
